(57) **CLAIM**

The ornamental design for a mounting frame for multiple tenor drums, as shown and described.

DESCRIPTION

FIG. 1 is a top front right perspective view of a mounting frame for multiple tenor drums showing our new design; FIG. 2 is a bottom front left perspective view thereof; FIG. 3 is a front elevational view thereof; FIG. 4 is a right side elevational view thereof; FIG. 5 is a rear elevational view thereof; FIG. 6 is a left side elevational view thereof; FIG. 7 is a top plan view thereof; and, FIG. 8 is a bottom plan view thereof.

The broken lines are included for the purpose of illustrating portions of the mounting frame and form no part of the claimed design.

1 Claim, 5 Drawing Sheets
